BOILER DRUM AND SOOT HOPPER
CONSTRUCTION

Ivar L. Langvand and Glen J. Schoessow, Barber-ton, Ohio, assignors to The Babcock & Wilcox Company, Rockleigh, N. J., a corporation of New Jersey

Application March 12, 1946, Serial No. 653,844

11 Claims. (Cl. 122—235)

1

The present invention relates to the construction and arrangement of walls for vapor generators heated by gaseous products of combustion. It is particularly directed to wall constructions in which water heating tubes form at least a part of the wall structure and act to absorb heat from the heating gases.

An object of our invention is to provide a wall structure associated with connected pressure parts of a boiler and comprising a soot hopper supported from one of the parts.

Another object of the invention is to provide a gastight boiler enclosure wherein a portion is formed as a soot hopper deriving support from a drum of the boiler, while another portion is formed as a wall associated with heat absorbing tubes connected to the drum.

It is also an object of the invention to provide an arrangement of pressure parts, including water cooling tubes of a boiler wall, and an associated dust hopper supported on the pressure parts, which permits differential temperature conditions of component portions while maintaining a gastight juncture of the portions.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of our invention.

Of the drawings:

Fig. 1 is an elevation view, in section, of a vapor generating unit incorporating our invention;

Fig. 2 is a section view taken on the line 2—2 of Fig. 1;

Fig. 3 is an enlarged side view of a portion of the apparatus shown in Fig. 1;

Fig. 4 is a section view taken on the line 4—4 of Fig. 3;

Fig. 5 is a view, in section, taken on the line 5—5 of Fig. 3;

Fig. 6 is a view, in section, taken on the line 6—6 of Fig. 3, with certain refractory material omitted;

Fig. 7 is a view, in section, taken on the line 7—7 of Fig. 6; and

Fig. 8 is a view, in section, taken on the line 8—8 of Fig. 4.

The steam generating unit illustrated in the drawings is of the general type disclosed in the

2

Bailey et al. patent, No. 2,326,513, issued August 13, 1943, wherein the furnace is laterally adjacent the upright banks of the boiler convection heating surfaces and the heating gas flow is directed through those convection banks by vertical baffles in a series of connected passes extending from a first pass adjacent the rear wall to a last pass adjacent the opposite front wall of the setting. As shown particularly in Fig. 1, the unit includes a water-cooled furnace 10 having a hopper bottom 11 and a plurality of groups of upright convection tubes connecting an upper drum 12 and a lower drum 13. The walls of the furnace are provided with water wall tubes which, with the exception of the front or burner wall (not shown), are closely spaced to form substantially continuous walls of water-cooled surfaces exposed to the radiant heat of the furnace. The tubes in the burner wall are spaced to permit bending the tubes in the plane of the wall to provide burner ports 14 for the insertion of fuel burners.

The tubes of the water wall are connected into the fluid circulating system of the steam generating unit in a conventional manner including the use of headers for some wall tubes while other wall tubes are directly connected to the boiler drums. The furnace rear wall is formed with a row of tubes 15 having the major portions of their lengths in closely spaced or contacting relationships in a common plane, connected at their upper and lower ends with the headers 16 and 17 respectively. The tubes 18 of the outer side wall 20 are bent in their lower portion 21 to form one side of the hopper bottom 11, while their upper portion 22 is bent to form a horizontally inclined roof for the furnace. The lower ends of the tubes 18 enter a header 23 which is connected with the lower drum 13 by tubes 19, while the upper ends of the tubes are directly connected with the upper drum 12 in two longitudinal rows, as shown. The opposite side of the hopper bottom is formed by a closely spaced series of tubes 24 extending between the header 25 and the upper drum 12 with water supply tubes 25a connected between header 25 and the lower drum 13. In the embodiment shown, all of the wall tubes are preferably of the same outside diameter, as for example 3 inches, in which instance they are spaced on substantially 3 inch centers.

Advantageously the water wall headers are circular in cross-section for ease of fabrication and the inherent strength of a circular member. Obviously it is desirable from a structural and

economic standpoint to select headers of the least possible diameter consistent with the fluid flow conditions therethrough. In addition, since the wall tubes are closely spaced, the header receiving those tubes must be drilled and the tubes correspondingly bent to enter the header tube seats in a spaced relationship to provide a header strength capable of withstanding the internal pressure therein, during periods of steam generation.

In the vapor generating unit illustrated in the drawings the boiler and its associated furnace are supported as a unit at the elevation of the lower drum 13 by structural means including upright steel columns 30 and 31. The lower drum 13 is supported on cradles 13a which, with columns 30 located directly beneath, provide bottom support for the lower drum 13 and for the banks of upright tubes extending upwardly therefrom. With this construction vertical expansion and contraction of the unit upon temperature changes occur relative to this predetermined horizontal support elevation. Certain features of the unit supporting structure herein shown are also disclosed, and are claimed, in the copending application of Glen J. Schoessow, Serial No. 654,239, filed March 14, 1946. As shown in Figs. 1 and 2, a soot hopper 32 extends longitudinally of the lower drum 13 for the full extent of the boiler setting with one longitudinal side thereof joined to the drum 13, while the upper margin of the opposite side of the hopper structure is connected to the superjacent side wall 39 of the setting. The hopper structure is formed of steel members lined with heat resistant refractory material and is longitudinally divided into a series of sections connected by expansion joints 33, as hereinafter described, to permit expansion and contraction thereof in a horizontal direction parallel to the axis of the drum 13. In the arrangement shown by Figs. 1, 2, 3, and 4, the hopper structure is carried by the drum 13 to which it is attached, as hereinafter described, while the side setting wall 39 above the hopper structure is carried by tubes 44 which form a part thereof and are in turn connected to and supported at their terminal ends by the drums 12 and 13.

Referring particularly to Fig. 4, a plate 34 which forms an innermost side of the hopper is bolted to a longitudinal bar 35 welded to the drum 13 and is inclined downwardly to a welded connection 34a with a horizontally disposed plate 36 forming the bottom of the hopper. A vertical plate 37 forming the outer side of the hopper, attached to plate 36 by a longitudinal weld, is connected to the casting plate 38 of the side setting wall 39 by a bolted flanged joint 40. From the flanged joint 40 the plate 37 is provided with an inclined off-set portion 41 and a vertical portion 42.

In addition to the bolted connection of the hopper plate 34 with the drum 13, the plate 36 is extended horizontally to a position below the drum 13 and attached to the drum support 30. A series of struts 61 are set on edge and connect the hopper 32 with the lower drum support 30. These struts are spaced longitudinally of the hopper to strengthen the hopper and are provided with vertical extension angles 62 to strengthen the vertical plate 37 of the hopper. In the construction shown, each separate section of the hopper, between the expansion joints 33, has a longitudinal dimension of from 6 to 7 feet and is provided with three struts 61 and extension angles 62 spaced therealong.

The weight of the hopper and the accumulated

solids is carried by a cantilever type of support from drum 13, the weight imposes a tensional stress upon the plate 34 while the struts 61 will be under a compression stress, thereby holding the hopper 32 in a substantially fixed position relative to the drum support.

The plates 50 and 51 forming the end walls of the hopper 32 are secured by bolts or the like to a flange 52 welded to opposite ends of the drum 13, and at the corners stiffening plates 53 and 54 are provided joining the plates 50 and 51 with the plate 37. A protective layer of refractory material 55 is provided for the internal wall surfaces of the hopper. The dust which is collected within the hopper may be periodically withdrawn through the spouts 56 in a convenient manner as through valve means so as to avoid leakage of air upwardly therethrough.

As shown in Fig. 8 with respect to wall plate 37, the expansion joint 33 extends transversely of the drum 13 and sectionalizes the hopper by inserting companion strips 63 and 64 between the inturned ends 65 and 66 of each longitudinal section of the hopper plate 37. One end 67 of the strips is welded together while their opposite ends are welded to the adjacent ends 65 and 66 of the inturned plate. The expansion joint extends substantially throughout the height of the vertical wall plate 37 and, from plate 37, transversely between sections of plates 36 and 34 up to the drum connection of the latter plate. Upon longitudinal differential expansion of portions of the hopper, as caused by a difference in temperatures, the companion strips 63 and 64 will spread adjacent the inturned ends of the joints, as for example 65 and 66, to a V shape which still retains its gastight connection between adjacent sections of plates 37, 36, and 34.

The upper setting side wall 39 is made up of the row of tubes 44, tile 47, insulation 48 and the outside casing 38, with the wall components supported on the tubes 44 which are subject to expansion and contraction with the other heated pressure parts of the boiler. The tile 47 forming the closure of the spaces between the tubes 44 extend vertically from a position adjacent the top of the hopper structure and the lower most tile are supported on the tubes through the combination of the tube saddles 46 and the longitudinally extending shelf angle 43 attached thereto by means of the bar 45. The saddles 46 are welded to the tubes 44 and the bars 45 are welded to the flange portions of the saddles.

In the construction described the tile and tube portions of the wall 39 will expand upwardly as a unit with the expansion of the tubes 44 and since the position of the hopper is rigidly supported by the drum 13, the connection between the upper portion 42 of the plate 37 and the saddle 46 is arranged to permit relative movement therebetween. This is accomplished by the use of a series of slotted holes 59 in the hopper plate portion 42 through which each saddle 46 and coacting shelf member 43 are held against the plate by a bolt 51. As shown in Fig. 6 a tubular spacer 58 and washer 60 are interposed between the head of the bolt 51 and the flange of the shelf member 43. The spacer is longer than the thickness of the plate portion 42 so that when the assembly is bolted together the saddle 46 may move relative to the hopper 32 in a vertical direction restricted to the dimensions of the slotted openings, and maintain a substantially gastight joint 58, as indicated.

The desirability of this type of construction and

the relatively slight difference in expansion and contraction of the component parts forming the joint between the hopper 32 and the wall 39 is apparent from a consideration of the temperatures to which the related parts are subjected. The temperature of different portions of the hopper, during operation of the vapor generating unit, will differ between a temperature approaching that of the drum 13 and tubes 44, to a lower temperature characteristic of the casing 38. With the hopper rigidly supported by the drum 13 and the inner elements of wall 39 movable vertically with the tubes 44 a sliding joint therebetween providing for a slight vertical movement is desirable. For example it has been found that the slotted holes 59 may be approximately $\frac{1}{8}'' \times 1\frac{1}{4}''$ when used with a $\frac{1}{2}''$ standard weight pipe spacer 58 and a $\frac{1}{2}''$ bolt 57 inserted therethrough, and provide adequate movement for the differential in expansivity of the parts.

We claim:

1. In a vapor generating unit having a horizontally disposed lower drum, means for supporting said drum, a row of tubes connected to said drum having a substantially vertical portion lying in a plane spaced from and parallel to the axis of said drum, refractory material cooperating with said tubes to form a substantially vertical wall of said vapor generating unit, a soot hopper between said drum and said wall, and means for supporting said hopper from said drum while maintaining said hopper substantially leak-proof during the operation of said vapor generating unit, said last named means comprising means for rigidly securing a side of said hopper to said drum, and means forming a leak-proof expansion joint between the opposite side of said hopper and said unit wall, said hopper having end walls joined to said sides and rigidly secured to said drum along longitudinally spaced arcuate portions thereof.

2. In a vapor generating unit having a horizontally disposed lower drum, means for bottom-supporting said drum, a row of tubes connected to said drum having a substantially vertical portion lying in a plane spaced from and parallel to the axis of said drum, refractory material cooperating with said tubes to form a substantially vertical wall of said vapor generating unit, a soot hopper between said drum and said wall, and means for supporting said hopper from said drum while maintaining said hopper substantially leak-proof during the operation of said vapor generating unit, said last named means comprising a longitudinal bar secured to said drum and affixed to an inclined side of said hopper, and a series of struts extending between and affixed to the supporting means of said drum and to the lower side of said hopper, said lower side having a rigid connection with said inclined side, said hopper having an upright side forming a continuation of said unit wall and slideably attached in leak-proof relationship thereto.

3. In a vapor generating unit having a horizontally disposed lower drum, means for supporting said drum at a fixed elevation and permitting longitudinal movement thereof upon changes in temperature, a row of tubes connected to said drum and arranged to cooperate with successive rows of refractory tile and with insulating material to form a substantially vertical wall of said vapor generating unit parallel to the axis of said drum, a soot hopper disposed between said drum and said wall and extending longitudinally of said drum substantially

throughout the width of said wall, and means for supporting said hopper in fixed relation to said drum while maintaining said hopper substantially leak-proof during the operation of said vapor generating unit, said last named means comprising a longitudinal bar welded to said drum and extending horizontally between and affixed to an inclined side of said hopper, a series of struts affixed to the supporting means of said drum and to the lower side of said hopper, a vertical side of said hopper slideably attached in leak-proof relationship to said vapor generating unit wall, means for discharging collected solid materials from the bottom of said soot hopper, and at least one vertical expansion joint dividing said hopper longitudinally thereof.

4. In a vapor generating unit having a horizontally disposed lower drum, a series of structural columns supporting said drum at a substantially fixed elevation and arranged for longitudinal movement of the drum thereon with changes in drum temperature, a row of tubes connected with said drum having a substantially vertical portion lying in a plane spaced from and parallel to the axis of said drum, a substantially vertical wall supported on said tubes and arranged to form one wall of said generating unit setting, a soot hopper between said drum and said wall, means for supporting said hopper at a substantially fixed elevation and longitudinally adjacent said drum comprising a bar longitudinally secured to said drum and affixed to an inclined side of said hopper, a series of struts affixed to the columns supporting said drum and to the lower side of said hopper, means forming a vertically expansible leak-proof joint connecting a vertical side of said hopper with said unit wall, end plates to said hopper attached to said drum and to the sides of said hopper, said end plates each having a portion extending exteriorly of said hopper and being attached to said drum within an arc embracing the position of said bar, means for removing collected solid materials from said hopper, and at least one vertical expansion joint dividing said hopper into longitudinal sections.

5. In a vapor generating unit having a horizontally disposed lower drum, means for supporting said drum at a substantially fixed elevation and arranged for longitudinal movement of the drum thereon with changes in drum temperature, a row of tubes connected with said drum having a substantially vertical portion lying in a plane spaced from and parallel to the axis of said drum, a substantially vertical wall supported on said tubes and arranged to form one wall of said generating unit setting, a soot hopper between said drum and said wall, means for supporting said hopper at a substantially fixed elevation and longitudinally adjacent said drum comprising a bar longitudinally secured to said drum and affixed to an inclined side of said hopper, a series of struts affixed to the means supporting said drum and to the lower side of said hopper, means forming a vertically expansible leak-proof joint connecting a vertical side of said hopper with said unit wall, end plates to said hopper attached to said drum and to the sides of said hopper, means for removing collected solid material from said hopper, and at least one vertical expansion joint dividing said hopper into longitudinal sections comprising a flanged end on the hopper section continuously welded at its end to one edge of a steel strip, a companion strip welded at its edge to the end of a corresponding

flange of an adjacent hopper section and the companion strips welded together at their edges opposite to the edges welded to said flanges.

6. In a vapor generating unit having an upper drum and a lower drum, means for supporting one of said drums, upright tubes extending in a row between said drums and connected at opposite ends thereto, means forming an upright wall of said unit at one side of said row, a soot hopper between said lower drum and said wall having an upright side wall horizontally spaced from said lower drum and terminating in an upper side wall portion adjacent said unit wall, means supporting said hopper from said lower drum, means forming a substantially gastight joint between said unit wall and said upper side wall portion of said hopper wall, and means tying said upper side wall portion to certain of said tubes for restraining said hopper wall against lateral movement relative to said row, said tying means comprising relatively movable portions.

7. In a vapor generating unit having an upper drum and a lower drum, means for supporting one of said drums, upright tubes extending in a row between said drums and connected at opposite ends thereto, means forming an upright wall of said unit at one side of said row, a soot hopper between said lower drum and said wall, said hopper having a pair of spaced side walls and a pair of spaced end walls interconnected and arranged respectively longitudinally and transversely of said lower drum, means for supporting said hopper from said lower drum comprising means rigidly securing one of said side walls to said drum along an upper edge portion and means rigidly securing each of said end walls to said lower drum along a lateral edge portion, means forming a substantially gastight connection between said unit wall and an upper portion of the other of said hopper side walls, and means for tying said upper hopper side wall portion to tubes of said row, said tying means having relatively movable components arranged to permit expansive and contractive movement of said tubes relative to said hopper.

8. In combination with an elongated boiler drum, a soot hopper arranged longitudinally adjacent said drum, said hopper having interconnected boundary walls comprising longitudinal walls and transverse walls extending respectively longitudinally and transversely of said drum, means for maintaining said transverse walls in substantially fixed position relative to opposite end portions of said drum, means forming an expansion joint between longitudinally adjacent sections of said longitudinal walls, said last named means including an end flange on one of said sections extending to one side of said longitudinal walls and opposing a similarly arranged flange on the next adjacent section, a pair of strip-like elements disposed between said opposing flanges and each terminating in edges at opposite sides of said longitudinal walls, means at one of said sides sealingly connecting an edge of each of said elements to the adjacent edge of a different one of said flanges, and means at the opposite side sealingly connecting an edge of one element to the adjacent edge of the other.

9. In apparatus forming a space enclosure associated with an elongated part subject to temperature variations, said apparatus having interconnected boundary walls comprising lateral wall portions extending longitudinally of said part and end wall portions extending transversely of

said part, means for maintaining said end wall portions in substantially fixed position relative to longitudinally spaced portions of said part, means forming an expansion joint between longitudinally adjacent sections of said lateral wall portions, said last named means including an end flange on one of said sections extending to one side of said lateral wall portions and opposing a similarly arranged flange on the next adjacent section, a pair of strip-like elements inserted between said opposing flanges and each terminating in edges at opposite sides of said lateral wall portions, means at one of said sides sealingly connecting an edge of each of said elements to the adjacent edge of a different one of said flanges, and means at the opposite side sealingly connecting an edge of one element to the adjacent edge of the other.

10. In a vapor generating unit having an upper drum and a lower drum, means for supporting one of said drums, upright tubes extending in a row between said drums and connected at opposite ends thereto, means forming an upright wall of said unit at one side of said row, a soot hopper between said lower drum and said wall having an upright side wall horizontally spaced from said lower drum and terminating in an upper side wall portion adjacent said unit wall, means supporting said hopper from said lower drum, means forming a substantially gastight joint between said unit wall and said upper side wall portion of said hopper wall, and means tying said hopper side wall to certain of said tubes for restraining said hopper wall against lateral movement relative to said row.

11. In a vapor generating unit having a horizontally disposed drum and having an upright wall arranged in horizontally spaced relation to said drum, said wall comprising upright fluid conducting tubes arranged as wall cooling elements and having lower ends connected to said drum, a soot hopper between said drum and said wall, and means for supporting said hopper from said drum while maintaining said hopper substantially leak-proof during the operation of said vapor generating unit, said means comprising means for rigidly securing a side of said hopper to said drum, and means forming a leak-proof expansion joint between the opposite side of said hopper and said unit wall, said hopper having end walls joined to said sides and rigidly secured to said drum along longitudinally spaced arcuate portions thereof.
